UNITED STATES PATENT OFFICE.

GEORGE W. TILL, OF PHILADELPHIA, PENNSYLVANIA.

TREMOLO ACTION FOR ORGANS.

Application filed February 19, 1921. Serial No. 446,297.

To all whom it may concern:

Be it known that I, GEORGE W. TILL, a citizen of the United States, residing in Philadelphia, Pennsylvania, have invented 5 certain improvements in Tremolo Actions for Organs, of which the following is a specification.

My invention relates to certain improvements in pipe organs of the type having two 10 or more distinct organ units and the main object of the invention is to provide means whereby the tremolo actions of all of the organ units will beat in unison.

A further object is to provide means 15 whereby the beat of the tremolo can be regulated at will, and a still further object is to provide means for operating the tremolos from any of the keys of the organ by increasing the pressure on the keys and momentarily increasing the volume of air supply 20 to the motors.

Another object is to operate the tremolo bellows through an interrupter and magnet and to drive the interrupter by an air engine 25 under the control of the organist and also to provide two motors and interrupters so that a great variation of the beat of the tremolos can be obtained.

In the accompanying drawings,

30 Fig. 1 is a diagrammatic view showing three organ units and a console and illustrating diagrammatically my improvements;

Fig. 2 is a plan view of the console in dotted lines and my improvements in full line;

Fig. 3 is a side view of the console in dotted lines and illustrating my improvements in full lines;

40 Fig. 4 is a plan view showing one of the air engines and the commutator;

Fig. 5 is a sectional view on the line 5—5, Fig. 4;

Fig. 6 is a front view of one of the tremolo boxes;

45 Fig. 7 is a side view of one of the tremolo boxes;

Fig. 8 is a sectional plan view on the line 8—8, Fig. 6;

Fig. 9 is an enlarged sectional view of the 50 lower portion of one of the tremolo boxes showing the air valve and controlling magnets;

Fig. 10 is a diagrammatic view showing a single motor; and Figs. 11, 12, 13 and 14 are 55 views of details of the invention.

Referring in the first instance to Fig. 1, 1,

2 and 3 are three organ units, such as the great organ, choir organ and swell organ. In large organs this number may be increased depending upon the size of the organ. 4 is the console having any number of banks of keys, stops and combinations, but as this invention only relates to the tremolos and the mechanism for operating them, I have shown all the other parts in dotted lines.

At each organ unit is a tremolo box referred to in Fig. 1, as 5, 6 and 7. At the console in the present instance are two motors 8 and 9. These are shown in the present instances as air motors, as I find that air motors run more evenly than electric or other motors. The motor 9 is shown in detail in Fig. 4 and is made up of a series of bellows 10 which actuate a crank shaft 11, 60 adapted to bearings 12 on the frame 13 of the motor. 14 is the air intake pipe, and valves 15, which are actuated by the crank shaft 11, open and close the exhaust passage 16 leading from the bellows. This is a 65 common form of air motor.

On the end of the shaft 11 is a contact drum 17 having in the present instance four V-shaped contact plates 18 separated by non-conducting material 19, Fig. 5 and resting on the drum is a contact arm 20 projecting from a rod 21 adjustably mounted in a bearing 22 forming a terminal. The rod is held in position by a screw 23 or other fastening. This construction forms a 70 circuit interrupter.

On adjusting the rod the contact plate 20 can be moved over the drum to increase or diminish the length of contact irrespective of the speed of the motor. The motors 8 and 9 are alike and each has a circuit interrupter. The contact of one motor is set near one end of its drum and the contact of the other motor is set near the opposite end so that on regulating the speed of the motors 75 the length of contact can be varied from one extreme to the other.

The terminal bearing 22 of each motor is connected by wires *a* to a binding post on each tremolo box 5, 6 and 7 and the drum of each motor is connected by a wire *b* through a switch to a battery *c* which in turn is connected by wires *d* to the other terminal of each tremolo box. A switch *e* under the control of the organist makes or 80 breaks the circuit of the motor 8 and the switch *f*, also under the control of the organ-

ist, makes or breaks the circuit of the motor 9 so that the drum of either motor can be brought into action or cut out at will.

I have shown the switches *e* and *f* as independent switches, but they may be of the interlocking type so that when one switch is thrown in the other cannot be thrown in at the same time.

The supply pipes 14 of the two motors 8 and 9 are connected to a common pipe 24 leading from any wind chest in order to supply sufficient air to drive the motors. In each pipe 14 is a main control valve 25 which controls the supply of air to the motors. These valves are operated by a rod 26 extending to the keyboard of the console, and on the rod are two arms 27 and 28. The arm 27 is connected by a rod 29 to an arm on the valve 25 of the motor 8 and the arm 28 is connected to an arm on the valve 25 of the motor 9, and on the opposite end of the rod is a handle 30 which is arranged to travel over a dial 31 on the case so as to indicate to the organist the amount of opening when the valves are turned.

The valves 25 are usually set in a given position and remain in this position as the motors are running continuously while the organ is in action and in some instances it is desirable to provide means whereby the organist can increase the speed of the motors to increase the beat of the tremolos at given places in the score to produce certain effects and this is accomplished by providing by-pass pipes 32 which pass around the valves 25 and in the by-pass pipes are valves 33. A vertical shaft 34 has an arm 35 connected to the valve of the motor 9 by a link 36 and an arm 37 is connected by a long rod 38 to a lever 39 which in turn is connected to the valve 33 of the motor 8, Fig. 2, and on the shaft 34 is an arm 40 which is actuated by a rod 41 operated by a treadle 42 through a lever 43, so that when the organist places his foot on the treadle the by-pass valves are opened to a greater or less extent and an increased amount of air is supplied to the motors and thus the speed of the motors is increased.

In order that the by-pass valves may be operated through the keys, I provide pivoted bars 44 which extend over the inner ends of the keys of each bank as shown in Figs. 2 and 3 and in such position that by an extra pressure on a key a bar will be turned on its pivot and as an arm 45 on each bar is connected by a rod 46 to a lever 40^a on the shaft 34 the shaft will be turned and the by-pass valves will be actuated.

The motors are driven continuously when the valves 25 are open, but are not connected to the tremolo boxes until one of the switches *e* or *f* is moved to close its circuit, depending upon which motor it is desired to use.

The organist can increase the tremolo beats

by either placing his foot on the treadle 42 or by pressing down on the keys.

The mechanism at each tremolo box is shown clearly in Figs. 6 and 9 inclusive. The box is connected through a passage 47 with the trunk 50 of the organ unit to which it is attached, so that it contains air under pressure at all times. 48 is an air outlet openings in the box of sufficient size to reduce the pressure in the box, and if the valve 49 which closes the opening is actuated rapidly, it will cause a tremolo in that particular organ unit.

In the present instance the box contains three pneumatics 51, 52 and 53. The pneumatic 51 is large and is connected directly to the valve 49. The bellows 54 is opened by a spring 55 and closed by the air pressure in the box. The closing of the bellows opens the valve 49. The interior of the bellows is connected by a passage 56 with an opening 57 to atmosphere and this opening is closed by a valve 58 on a stem 59; under the control of the second pneumatic 52 and spring 71, the spring tends to close the valve and when the interior of the bellows is open to atmosphere the air pressure in the box will force the valve 58 off its seat and seat the valve 60 on the inside of the box.

The bellows of the pneumatic 52 is connected by a passage 61 to an opening 62 to atmosphere. The opening 62 is closed by a valve 63 on a rod 64 controlled by the pneumatic 53 and spring 72. The interior of the bellows of the third pneumatic 53 is connected by a passage 65 with a valve chamber 66, Fig. 9, having a seat 67 on which rests an armature valve 68. The passage 73 within the seat is open to atmosphere.

69 is a magnet so located in respect to the armature valve that when energized the armature valve will be raised off its seat to allow air to be exhausted from the bellows of the third pneumatic 53. The magnet and the armature valve form the magnetic valve referred to in the claims. As the magnets are connected through binding posts 70 to which wires *a* and *d* are attached, the valve is under the control of the interrupter of the motors when one or other of the switches is closed.

The moment the armature valve is opened one after the other of the three pneumatics is actuated, the pneumatic 51 moving the large valve 49 off of its seat and momentarily allowing a given quantity of air to escape from the chest 50 through the tremolo box 5.

In Figs. 1 and 2 two motors are shown and these motors are located in the console of the organ. In Fig. 10 I have shown a single motor and this motor is located near the organ units and some distance from the console and may be connected with one of the air trunks without the regulating valves 25

or 33 and in this case the motor will be driven at a given speed and the contact arm may be adjusted to a position desired and fixed.

- 5 A switch *g* at the console may be provided to open or close the circuit leading from the interrupter to the magnetic valve or valves at the tremolo box or boxes. The switch is shown as mounted on the rod 26, in 10 the present instance. In fact the motor may be placed at any convenient place and one or more may be used and one or more tremolo actions may be operated, depending upon the size of the organ and the number of organ 15 units and the desire of the organist in developing the tremolo action.

In order to prevent the continuous opening of the tremolo pneumatic, when either of the motor valves is closed, I provide the rod 34 20 that controls each valve operating mechanism with a switch *g'* consisting of a cylinder 73, in the present instance having a non-conducting section 76 and two terminal plates 77 and 78 bearing against the cylinder, as 25 shown in Fig. 14. The non-conducting section is so placed that when the valves are closed it is in contact with one of the terminal plates and breaks the circuit leading from the interrupter to the magnetic valve. The 30 moment either mechanism is turned to open its valve, the circuit is closed, as the non-conducting section leaves the terminal.

I stated that on operating the by-pass valve the tremolo action may be increased in 35 speed, leaving the main valve in the position to which it was adjusted, but when it is desired to decrease the speed as well as to increase it, then I move the main valve to the closed position and operate the by-pass valve 40 so that it can be moved the full range so as to increase or decrease the speed of the tremolo.

While I have illustrated a certain form of pipes, connections, and valves for supplying 45 the motors with air, it will be understood that any suitable form of pipes and valves may be used without departing from the essential features of the invention.

I claim:

50 1. The combination in an organ, of a tremolo box; means, in the box, for producing a tremolo; a motor; an interrupter driven by the motor; and a magnetic valve, under the control of the interrupter, acting to release 55 air from the mechanism in the tremolo box as the interrupter is operated.

2. The combination in an organ, of a tremolo box; means, in the box, for producing a tremolo; a motor; an interrupter driven by 60 the motor; a magnetic valve, under the control of the interrupter, acting to release air from the mechanism in the tremolo box; and a switch, in the electric circuit, located at the 65 console of the organ for controlling the tremolo mechanism.

3. The combination in an organ, of a series of independent organ units; a tremolo box for each unit of the organ; and a single mechanism for actuating the tremolo mechanism of the several boxes in unison. 70

4. The combination in an organ, of a series of independent organ units; a tremolo box for each organ unit; a motor; an interrupter driven by the motor; and a magnetic valve in each tremolo box controlling the exhaust 75 of air from the tremolo mechanism in the boxes so that the tremolo mechanisms of the several organ units will be operated in unison.

5. The combination in an organ, of a series 80 of organ units; a tremolo box for each unit; a motor; an interrupter driven by the motor; a magnet at each box; an armature valve at each magnet arranged to control the escape of air from the tremolo mechanisms of the 85 boxes; and a switch in the electric circuit leading from the interrupter to the magnet, said switch being located at the console of the organ.

6. The combination in an organ, of a tremolo box; a magnetic valve controlling the exhaust of air from the box; a motor; an interrupter driven by the motor, said interrupter having a drum with tapered contact plates; and a contact arm arranged to bear 95 upon the plates, said arm being adjustable over the face of the drum, the interrupter being electrically connected to the magnet of the tremolo box.

7. The combination in an organ, of a tremolo box; pneumatic tremolo mechanism in said box; a pneumatic valve controlling the exhaust of air from said pneumatic mechanism; an air motor; an interrupter driven by the motor and having a drum and an arm 100 bearing upon the drum, the interrupter being wired to the magnet; means for applying air to the motor; a valve for regulating the supply of air to the motor; and means, at the console, for controlling said valve. 110

8. The combination in an organ, of a tremolo box; pneumatic mechanism therein; a pneumatic valve controlling the exhaust of air from the pneumatics; an air motor; an interrupter driven by said motor and having 115 a drum and a contact arm; a pipe for supplying air to the motor; a main valve in the pipe controlling the flow of air through the pipe, means, at the console of the organ, for operating the valve; a by-pass in said pipe; 120 a valve in said by-pass; and means, also at the console, for controlling the by-pass valve.

9. The combination in an organ, of a tremolo box; pneumatic tremolo mechanism 125 in the box; a pneumatic valve controlling said mechanism; an air motor; and interrupter driven by said motor and having a drum and a contact arm, said interrupter being wired to the pneumatic valve; an air sup- 130

ply pipe for the motor; a valve in said pipe; means, at the console of the organ, for opening and closing said valve and arranged so that the valve can remain open or closed; a 5 by-pass in the pipe; a valve in the by-pass; means, at the organ, controlling the by-pass valve so that the organist can momentarily increase the amount of air delivered to the motor in order to change the beat of the 10 tremolo.

10. The combination in an organ, of a tremolo box; pneumatic mechanism in the box; a pneumatic valve controlling the said mechanism; an air motor; an interrupter 15 driven by said motor and having a drum and a contact arm, said interrupter and arm being wired to the pneumatic valve; an air supply pipe for the motor; a valve in said pipe; means, at the console of the organ, for opening and closing said valve and arranged 20 so that the valve can remain open or closed; a by-pass in the pipe; a valve in the by-pass; means extending over the keys of the console; and means, at the pedal, for actuating the by-pass valve so as to increase momentarily the amount of air delivered to the motor to increase the beat of the tremolo.

11. The combination in an organ, of a tremolo box; a pneumatic tremolo mechanism in the box; a pneumatic valve controlling said mechanism; two motors; an interrupter driven by each motor, the two interrupters being wired to the pneumatic valve; independent means for regulating 30 the power of each motor; and means for adjusting each interrupter so that the length of 35 the beat of the tremolo mechanism can be varied.

12. The combination of an organ tremolo 40 box; pneumatic mechanism in said box; a pneumatic valve controlling said mechanism; a motor; an interrupter driven by said motor, said interrupter being wired to the

pneumatic valve; means for controlling the speed of the motor; a console; controlling 45 mechanism at the console; and switch mechanism for throwing said controlling mechanism into and out of position in respect to the keys.

13. The combination in an organ, of a 50 tremolo box; pneumatic mechanism therein; a pneumatic valve controlling said mechanism; a motor; an interrupter driven by the motor, said interrupter having a drum with V-shaped contacts; a contact arm bearing 55 upon the drum; and means for adjusting the arm over the surface of the drum so as to increase or diminish the length of the beats of the tremolo.

14. The combination in an organ, of a 60 series of organ units, each unit having a tremolo box; pneumatic tremolo mechanism in each box; a magnetic valve controlling the mechanism at each box; two pneumatic motors; an interrupter driven by each motor, 65 said interrupters being electrically connected to the several magnetic valves so that, when either of the interrupters is in motion, the magnetic valves will be operated in unison; a switch in each electric circuit leading from 70 the interrupters to the valves; means controlling the flow of air to the two motors; and means for regulating the amount of air and independently controlling momentarily the flow of air to the motors. 75

15. The combination in an organ, of a tremolo box; a magnetic valve at the tremolo box; a motor; an interrupter driven by the motor and electrically connected to the magnet of said magnetic valve; means for 80 controlling the supply of energy to the motor; and a switch between the interrupter and the magnetic valve so arranged that, when the motor is stopped, the circuit is broken.

GEORGE W. TILL.
